UNITED STATES PATENT OFFICE.

THOMAS J. MCKINNON, OF LIVINGSTON, TEXAS.

WELL-BUCKET.

1,259,759.

Specification of Letters Patent. Patented Mar. 19, 1918.

Application filed December 15, 1916. Serial No. 137,151.

To all whom it may concern:

Be it known that I, THOMAS J. MCKINNON, a citizen of the United States, and a resident of Livingston, in the county of Polk and State of Texas, have invented a certain new and useful Improvement in Well-Buckets, of which the following is a specification.

This invention relates particularly to a bucket adapted to be used for cleaning and also for drawing water from drilled wells.

The bucket has a cylindrical cutting edge which loosens and scrapes off the silt and other trashy matter that may adhere to the well tube.

The novel features of the invention are hereinafter described with reference to the accompanying drawing in which—

Figure 1 is a vertical section through the lower portion of the bucket, showing the valve in closed position;

Fig. 2 is a similar view showing the valve in open position;

Fig. 3 is a horizontal section through the cylindrical portion of the valve, showing openings for the ingress of material to the bucket;

Fig. 4 is a fragmentary vertical section showing a modified form of valve;

Fig. 5 is a fragmentary sectional view showing the arrangement when the shelf and conical member are made of separate pieces, and

Fig. 6 is a fragmentary sectional view illustrating the use of a common lift valve with the bucket.

Referring to the drawings, 1 represents the body portion of the bucket which is cylindrical in form. The lower edge 2 of said bucket is crimped inwardly and upwardly to form an annular flange, designed to secure the lower edge of the conical or funnel-shaped member 3, the cross section of which decreases uniformly toward its smaller end.

45 This member 3, which is open at both ends, has its upper portion flared outwardly to form a shelf 4, which in turn has its outer edge down turned and soldered or otherwise secured to the body portion 1 of the bucket.

50 The shelf 4 serves to rigidly brace the conical member 3, and prevent any warping thereof, and also forms a seat for the valve 5. The said valve 5 which is slidable in the opening 9 defined at the smaller end of the

55 conical member 3, consists of a cylindrical

portion 6, closed at its upper, and open at its lower end, and provided with openings 7 for the admission of water when the valve is in open position, as shown in Fig. 2. The lower edge of the cylindrical portion 6 is flared outwardly at an angle to form a flange 8, adapted to engage against the walls of the cone 3 near the opening 9 of the valve seat, for the purpose of limiting the upward movement of the valve, as shown in Fig. 2.

The valve proper consists of a disk 10 of leather or other suitable material, seated on the shelf 4. The disk 10 is interposed between and riveted or otherwise secured to the closed end 11 of the valve holder or cylindrical member 6, and a reinforcing plate 12. The said plate 12 extends slightly beyond the edge of the opening 9, and serves to stiffen the valve 10 and heat it evenly on the valve seat.

75 It will be readily seen that, when the bucket is lowered to the bottom of the well, the lower edge of the bucket which approximates the well in diameter and thus works in loose sliding contact therewith will cut away and loosen the silt and other trashy matter which adheres more or less to the well. The conical member 3 will simultaneously exert a pressure upon the material, forcing it to raise the valve 10 and flow 80 through the openings 7 into the bucket.

85 It will be understood that the above described bucket may also be used simply for raising water, as the weight of the bucket is sufficient to sink the bucket, thus causing 90 the valve to raise and admit the water.

In Fig. 4 I have shown a modified form of bucket, in which I have retained the same structural advantages, but have substituted for the valve described above a leather flap 95 valve 10', having a reinforcing plate 12' secured thereto. The valve 10' is riveted or otherwise secured to the shelf 4' at a point to one side of the inlet opening defined at the end of the conical member.

100 It will be appreciated that the structural details of the invention may be altered without in any way impairing its efficiency or departing from the scope of the appended claims.

105 If desired the shelf 4 and conical member 3 may be made in separate pieces, as indicated in Fig. 5, and in such instance the shelf would be equipped with a downturned flange portion 4', defining the opening for 110

receiving the valve, which flange would be soldered or otherwise secured to the upper end of the conical member 3.

If desired I may, upon occasion, use an ordinary lift valve in connection with the bucket, and such valve is indicated in Fig. 6, and constitutes principally a flexible member 15 for fitting over the opening in the shelf 4, a rigid piece 16 overlying the flexible member 15, and a substantially inverted U-shaped strip 17 suitably connected with the members 15 and 16 and having its ends projecting as indicated downwardly through the opening defined at the upper end of the 15 conical member 3.

I claim:

1. A well bucket consisting of a cylindrical body portion, an internal conical member open at both ends and secured to 20 the lower edge of the body, and a valve and

valve holder, the latter being adapted to slide in the top of the conical member and having an outturned flange at its lower edge which, when the valve holder rises, engages the conical member and thus serves as a stop, as described.

2. A well bucket comprising a body of uniform diameter throughout its length, a conical member open at both ends and arranged within the lower portion of said body and having its lower edge flared outwardly so that as the valve rises it comes in contact with the cone, as described.

3. A well bucket comprising a cylindrical body, a conical open-end member arranged within the lower portion of said body and having its lower flaring edge secured to the latter, thus forming a cutting edge whose outer side is cylindrical, as described.

THOMAS J. MCKINNON.
